UNITED STATES PATENT OFFICE.

JOHN T. McCORMICK, OF SAN FRANCISCO, CALIFORNIA.

FIREPROOF WALL OR PARTITION FOR BUILDINGS.

SPECIFICATION forming part of Letters Patent No. 618,462, dated November 1, 1898.

Application filed April 8, 1898. Serial No. 676,894. (No model.)

To all whom it may concern:

Be it known that I, JOHN T. McCORMICK, a citizen of the United States, residing in the city and county of San Francisco, State of California, have invented an Improvement 5 in Fireproof Walls or Partitions for Buildings; and I hereby declare the following to be a full, clear, and exact description of the same.

My invention relates to improvements in 10 fireproof construction of walls and partitions for buildings.

It consists of the parts and the constructions and combinations of parts hereinafter described and claimed.

15 Figure 1 is a view of one form of my improved construction. Fig. 2 shows another method of connecting the bars. Fig. 3 shows an arrangement in which no air-space is left between the two walls of the partition.

20 The object of my invention is to provide an improved and economical method of building intermediate walls and partitions in buildings and in making the same fireproof and either with or without an intermediate air- 25 space.

A represents vertical bars or studding, which may be made, say, three inches, more or less, in width and standing transversely of the proposed partition. Through these 30 upright bars, as shown in Fig. 1, are made slots or holes B, which are punched close to the edges of the partitions, and the strips C are then passed through these holes and twisted, so that they are locked in the holes, 35 and the bars thus lie approximately horizontal, with their edges flush or in the same plane with the edges of the bars A.

In punching the holes B care is taken to 40 punch them at such a distance from the edges of the bars A that when the bars C have been thus twisted their outer edges will lie in the same plane with the edges of bars A. The wire network or other form of metallic lathing is then secured to the edges of the bars, 45 forming a continuous smooth vertical surface upon which the plaster is afterward laid.

The bars A are slotted on both edges, and the bars C are thus introduced on both edges of the bars A, and, as here shown, they are alternated, so that the bars C upon one side

are placed approximately intermediate between those on the opposite side.

The lathing-surface being applied to both sides will form a double partition, with an interior air-space between, the plaster making 55 the bond with the vertical network in the usual manner.

Another method of securing the bars A and C together is to slot the bars A horizontally instead of vertically, and the slots are made 60 of a width equal to that of the bars C, so that the bars C may be slipped through the slots.

The bars C are each of them notched, as shown at D, the notches coinciding with the position of the vertical studs A, so that when 65 the bars C have been slipped through to their proper position each of the slots D will lie in the plane of the vertical studs A.

The slots D are of a depth equal to the distance between the ends of the horizontal holes 70 B and the edges of the vertical bars A, so that when the bars C have been pushed forward so that the slots D interlock and engage with the holes B the edges of the bars C will be in the plane of the vertical bars A. The bars 75 are then locked in this position by means of keys or wedges E, which are driven in behind them, thus securing the whole structure together in a firm manner. The metallic lathing is then applied to the opposite sides of 80 the proposed wall or partition, as before described.

In some cases I have found it desirable to make the partition without any intervening air-space. In this case the vertical bars A 85 are made smaller in width and only one series of holes are punched through them. The transverse bars C are then inserted and locked by either of the previously-described methods, and the metal lath is attached to one side. 90 The plaster is then applied upon one side of the partition. What is known as the "key," formed by the plaster oozing through to the opposite side, projects in a rough irregular surface, the outer side being made smooth in 95 the usual manner. After this coating of plaster has become sufficiently set another coating of plaster is applied on the roughened side formed by the key of the first coat, and this key forms a sufficient hold for the second 100

coat upon the opposite side, thus making a solid plastered wall, comprising two coats of plaster upon opposite sides of the lathing, and correspondingly thickening the wall, but leaving no intermediate air-space.

Having thus described my invention, what I claim as new, and desire to secure by Letters Patent, is—

1. A wall-partition comprising the vertical and horizontal metal bars directly interlocked at their points of intersection and with their edges approximately in the same plane.

2. A wall or partition comprising vertical bars standing transversely to the plane of the partition having slots made through them at points inside of their opposite edges, horizontal bars adapted to pass endwise through said slots, and a means for locking them directly in said slots with their edges approximately coinciding with the plane of the edges of the vertical bars.

3. A wall or partition consisting of vertical bars standing transversely to the plane of the partition having slots or holes made through them near but inside of their opposite edges, horizontal bars passing endwise through said slots and means in said slots for locking said

bars together with their edges approximately coinciding with the plane of the partition upon opposite edges of the vertical bars, and metallic lathing secured to said bars adapted to receive coatings of plaster upon opposite faces of the proposed partition.

4. A wall or partition consisting of vertical and horizontal bars with the horizontal bars passing endwise through the vertical bars at points inside of the outer edges of the same, with devices for interlocking said bars at their points of intersection so as to form a double series of alternating horizontal bars upon opposite edges of the vertical bars with their outer edges approximately in the plane of the two sides of the partition, metallic lathing secured to a framework thus formed and having plastered surfaces formed upon opposite sides whereby an intermediate air-space is provided.

In witness whereof I have hereunto set my hand.

JOHN T. McCORMICK.
